POLISHING MACHINE FIXTURE

Hugh Anderson, Detroit, Mich., assignor, by
mesne assignments, to Houdaille-Hershey Cor-
poration, Detroit, Mich., a corporation of Mich-
igan

Application April 23, 1938, Serial No. 203,974

4 Claims. (Cl. 51—216)

This invention relates to the polishing art, particularly the polishing of objects such as impact bars for bumper structures for automotive vehicles. In polishing machines for this work, the bumper bars to be polished are supported on a belt or other suitable conveyor to be carried through the polishing fields, the bars being mounted to be carried longitudinally in engagement with the polishing wheels. Sometimes the bumper impact bars have slight twists or edge warp or other condition which may prevent their proper and accurate application to the polishing wheels for accurate and uniform polishing thereof unless the bars may readily adjust and align themselves for proper application to the polishing wheels throughout their extent.

The object of the invention is to provide improved support units or fixtures which may be mounted on the conveyor at regular intervals to be spanned by the bars to be polished and which fixtures or supports permit the bars to move readily laterally so that any slight twist, edge warp, or other irregularity may be properly applied to the polishing wheels. To this end, the fixtures or supports comprise each a base structure adapted to be secured to a conveyor and a table structure on which the ends of bars rest, with the table structure mounted on the base structure by means of roller elements so that the table structure may readily shift laterally to follow the movement of the bars during their application to the polishing wheels.

An efficient embodiment of my invention is shown on the drawing, in which drawing:

Figure 1 is a side elevation of a conveyor structure with one of my improved supporting units or fixtures thereon and showing the fixture engaged by bars to be polished;

Figure 2 is a plan view of the fixture; and

Figure 3 is a section on plane III—III Figure 1.

On the drawing, 10 represents more or less diagrammatically a belt or other conveyor traveling in the direction of the arrow. On this conveyor are mounted the supporting units or fixtures at properly spaced intervals to be spanned by the objects to be polished, as for example, automobile bumper impact bars B. As shown, each unit comprises a base structure which may be in the form of a length of channel bar 11 with its flanges extending upwardly, the bar being secured to the conveyor along its transverse median line as by bolts 12. The flanges are spanned at their ends by bearing plates 13 and 14 respectively and at a middle

point by a bearing plate 15 and these plates may be secured to the flanges as by welding.

The table structure comprises a base plate 16 having retainer blocks 17 at its ends and secured against the under side of the plate in alignment with the bearing plates 13 and 14, each retainer block having elongated recesses or pockets 18 for bearing elements such as balls 19, the balls engaging the respective bearing plates 13 and 14. At the center of the table 10 plate 16 and secured against the under side thereof is a retainer plate 20 having the retainer recess 21 for a bearing element such as a ball 22, the ball engaging the intermediate bearing plate 15 on the base 11, the table structure being 15 mounted on the base 11 by the bearing elements. On the bearing plate 15 for the intermediate or center bearing ball 22 are retainer bars 23 extending transversely relative to the base 11 for limiting the longitudinal movement of the 20 table on the base.

Mounted on the bearing plates 13 and 14 along the outer ends thereof are guard members 24 which may be lengths of channel bar with their flanges extending inwardly, the lower flanges 25 being secured by welding to the bearing plates 13 and 14, and the upper flanges 26 overhanging the ends of the table plate 16 so as to hold the table to the base 11. The table structure may, however, be shifted readily laterally and also 30 turned on the base, the rotating or turning movement being limited as by means of stop pins 26 extending upwardly from the projecting ends of the bearing plates 13 and 14 to be in the 35 path of the ends of the table plate 16.

The table plate 16 supports an upper deck 27 above its front or advancing end. This deck may be a plate of metal having its front portion bent down to form a supporting leg 28, and its rear end supported on a cross bar 29 on the table base, the bar 29 being secured to the table base and the deck 27 being secured to the bar and to the base so as to form a rigid part of the table structure. The deck 27 is shown provided with 40 a number of transversely extending slots 30 which are arcuate for receiving the ends of bumper bars which are transversely curved.

Above the table base 16 along the rear or trailing end thereof is a lower deck 31 which 50 may be in the form of a plate secured to cross bars 32 which are mounted on the table base 16 and are secured thereto. Secured to extend along the side edges of the deck 31 are guard rails 33 whose upper edges may be in the plane 55

of the upper face of the higher deck 27, as shown on Figure 1.

The units are mounted on the conveyor at spaced intervals depending upon the length of the bars to be polished. The lower decks 31 of the tables of the units support the advancing ends of the bars while the higher decks 27 support the trailing ends of the bars, these trailing ends extending into the notches 39 so that the bars are coupled to the units to travel therewith through the fields of polishing rolls 34. The difference in height of the lower and upper decks is substantially the distance that the trailing ends of the bars extend through the coupling slots 30 so that the polishing pressure may be more uniform throughout the extent of the bars. The anti-friction support of the table structure on the base 11 of the unit will permit the table structure to readily follow displacement of the bars while subjected to the polishing rolls so that any portions of the bars in the form of slight twists or warp or other irregularities may be properly presented to the polishing rolls for efficient and uniform polishing of the bars. The stop pins 26 are located so as not to interfere with the movements of the table structures during polishing operations but the pins will prevent accidental displacement of the table structures from their supporting bases 11. The center bearing ball 22 will permit ready oscillation of the table structure to follow the movements of the supported bars during the polishing operation.

I have shown a practical and efficient embodiment of my invention but I do not desire to be limited to the exact construction, arrangement and operation shown and described as changes and modifications may be made which will still come within the scope of the invention.

I claim as follows:

1. The combination with the conveyor of a polishing machine, of polishing fixtures applied to the conveyor to be spanned by bars to be polished, each fixture comprising a base structure secured to the conveyor, a table structure for supporting the ends of the bars to be polished, roller elements supporting said table structure on the base structure for lateral and oscillatory movement of the table structure on the base structure to enable said table structure to readily follow the movement of the bars during polishing thereof, and restraining means engageable by said

roller element for limiting such lateral and oscillatory movement.

2. The combination with the conveyor of a polishing machine, of polishing fixtures applied to the conveyor to be spanned by bars to be polished, each fixture comprising a base structure secured to the conveyor, a table structure for supporting the ends of the bars to be polished, rolling bearing elements between said structures arranged to support said table structure for lateral and oscillatory movement on the base structure to follow the movement of the bars during polishing thereof, and restraining recesses in one of said structures for said roller element for limiting such lateral and oscillatory movement. 15

3. The combination with the conveyor of a polishing machine, of polishing fixtures applied to the conveyor to be spanned by bars to be polished, each fixture comprising a base structure secured to the conveyor and a table structure for supporting the ends of the bars to be polished, a bearing ball interposed between said structures intermediate the ends thereof, guide recesses in said structures for said bearing ball arranged to cooperate with said ball to prevent longitudinal movement of the table structure on the base structure but to permit lateral and oscillatory movements to enable the table structure to readily follow the movement of the bars during polishing thereof, and roller bearing elements between the ends of said structures for support thereof during oscillatory or lateral movement of the table structure. 20 25

4. The combination with the conveyor of a polishing machine, of polishing fixtures applied to the conveyor to be spanned by bars to be polished, each fixture comprising a base structure secured to the conveyor and a table structure for supporting the ends of the bars to be polished, a bearing between said structures intermediate the ends thereof arranged to restrain the table structure against longitudinal movement on the base structure but to permit lateral and oscillatory movement of the table structure on the base structure, and roller bearing element between the ends of said structures for guiding the lateral and oscillatory movement of the table structure, said lateral and oscillatory movement of the table structure enabling it to readily follow the movement of the bars during polishing thereof. 40 45
